UNITED STATES PATENT OFFICE.

HENRY KOHLMYER, OF LORAIN, OHIO, ASSIGNOR TO CORNELIUS KOHLMYER AND ADOLPH KOHLMYER, BOTH OF LORAIN, OHIO.

METALLIC TIE FOR RAILWAYS.

1,198,458.

Specification of Letters Patent. Patented Sept. 19, 1916.

Application filed August 19, 1915. Serial No. 46,255.

To all whom it may concern:

Be it known that I, HENRY KOHLMYER, a citizen of the United States, residing at Lorain, in the county of Lorain and State of Ohio, have invented certain new and useful Improvements in Metallic Ties for Railways, of which the following is a specification.

This invention relates to metallic ties, but more especially to this style of tie for street railways, and although embodying the same principles as my former Patent No. 1,114,890, it is an improvement thereof, as the present design can be manufactured at a lower cost, the main object of this invention being to provide a metallic tie having resilient properties, which can be rolled from a single piece of material.

For a full understanding of the invention, reference will be had to the accompanying drawings, which simply illustrate a preferred embodiment thereof, and the novel features of the invention will be distinctly pointed out in the appended claims.

In the drawings like characters of reference indicate corresponding parts.

Figure 1 is an end view of a metallic tie embodying my invention, Fig. 2 is an end view of the metallic tie before the base is rolled out for forming the hollow resilient base member, Fig. 3 is an end view showing a slight modification of Fig. 1, and Fig. 4 illustrates another modification.

In the drawings, 1 represents the head of a rolled steel tie, which head may be of any desired design, and 2 the web formed integral therewith. A base 3, similar to the head except that it is heavier and of greater width, is formed integral with the lower longitudinal edge of the web, and the whole resembles an ordinary I-beam, as shown in Fig. 2. The sides 4 and 5 of the base 3 are rolled into plates, and these plates are rolled into a hollow resilient base member, by first being inclined slightly downwardly to form top plates 6, the outer longitudinal edges of which turn under and into horizontal base plate 7 and 8. The free longitudinal edges of the base plates may simply meet as in Fig. 1, or these opposite longitudinal edges may be welded solidly together as illustrated in Fig. 3 at 9.

In the modification shown in Fig. 4, the

tie is formed of a single plate. The head consists of a flat plate 10 and undeturned downwardly inclined plates 11, which bend downwardly to form slightly diverging web plates 12. The hollow resilient base member is then formed from the web plates as already described, except that the horizontal base plates 13 are narrower and their opposite longitudinal edges 14 are in spaced relation.

It will be understood that the construction of metallic ties as herein disclosed is also applicable for rails; and also that any suitable provisions may be made in the head of the tie for securing rails thereto, or in the base member for fastening the tie to its foundation.

Having fully described my invention, what I claim is:

1. In a metallic tie, the combination of a head, a web carrying the head, and a base member supporting the web, the base member consisting of a pair of resilient plates

bent outwardly from the sides of the web, the plates being turned downwardly and inwardly, and the free longitudinal edges of the plates being secured together, substantially as described.

2. In a metallic tie, the combination of a head, a web formed integral with the head, a base consisting of a pair of sides extending from the sides of the web, the base being formed integral with the web, the sides of the base being formed into plates, the plates being bent outwardly and downwardly and turned inwardly with their free edges adjacent to each other to form a hollow resilient base member, substantially as described.

3. In a metallic tie, the combination of a head, a web formed integral with the head, a base consisting of a pair of sides extending from the sides of the web, the base being formed integral with the web, the sides of the base being formed into plates, the plates being bent outwardly and downwardly and turned inwardly to form a resilient base member, and the free opposite longitudinal edges of the inwardly turned plates being welded together, substantially as described.

In testimony whereof I affix my signature.

HENRY KOHLMYER.
